UNITED STATES PATENT OFFICE.

CHARLES WILLIAM ALEXANDER TAYLOR, OF DUNSTON-UPON-TYNE, ENGLAND.

APPARATUS FOR LOWERING AND HEAVING SHIPS' BOATS.

1,283,965.

Specification of Letters Patent. Patented Nov. 5, 1918.

Application filed May 21, 1918. Serial No. 235,786.

To all whom it may concern:

Be it known that I, CHARLES WILLIAM ALEXANDER TAYLOR, of Kyrstyville, Holm-side avenue, Dunston-upon-Tyne, England, 5 a subject of the King of Great Britain, have invented certain new and useful Improvements in or Relating to Apparatus for Lowering and Heaving Ships' Boats, of which the following is a specification.

10 This invention relates to apparatus for raising and lowering ships' boats of the type in which a davit or derrick member is hinged or pivoted and, in lowering, moves downward and carries the boat outward 15 clear of the ship's side.

Under my invention I provide, in combination with the davit or derrick member, hereinafter referred to as the davit, a hinged or pivoted lever or strut member which is 20 so connected to the davit that, as the davit moves downward, the strut member moves upward, both the davit and the strut member carrying the rope or other fall, the arrangement being such that as the davit member moves downward and the leverage exerted by the load increases the strut member in moving upward bears the load thereby relieving increasingly the stress upon the davit and preventing the same bending or breaking. 25 The davit may be so arranged that as it moves angularly downward it may also move or slide outward thereby giving it a greater range and moving the boat farther away from the ship's side.

30 Preferably, I use a single davit and secure its lower end pivotally in brackets on the boat deck at a short distance from the ship's side and I connect its upper end, by means of one or more links, to the upper end 35 of a strut member which is hinged or pivoted at the ship's side. As the davit is linked to the strut member the two move together, the strut member rising toward the vertical as the davit member moves downward and outward and, contrariwise, the 40 strut member moves toward the horizontal as the davit member moves toward the vertical and inboard. In certain cases where it is desired to move the boat as far away from the ship as possible during the lowering operation the davit is made with sliding blocks or with rollers at its pivotal end, the 45 blocks, or the rollers, moving in guides secured to the boat deck, and this end of the 50 davit is connected to the strut member in

such manner that, as the strut member moves, it pulls the bottom of the davit along the guides and moves the davit bodily outward the davit thus having a combined angular and sliding motion the sliding movement being outward during lowering and inward during hoisting.

I may use one or more davits for raising and lowering the boat but I prefer to use one, and, when so doing, in order to avoid 60 too sharp an angle, for the boat's slings where connected to the hoisting rope thus tending to draw the ends of the boat together, I may use a pulley mounted in a frame having laterally projecting arms 65 through which a central pin or axle will pass and, on this central pin, a pulley is arranged and is free to revolve, the frame being so made as to prevent the central pin from bending. From the ends of the pin 70 the slings lead down and are attached to the boat fore and aft. The pulley in the frame works in conjunction with a pulley at the end of the davit the fall rope passing around both.

In order that my invention may be clearly understood I have hereunto appended explanatory sheets of drawings whereon I have shown, by way of example, methods of carrying out the invention.

85 Figure 1 is a side elevation of the improved apparatus.

Fig. 2 is a plan of the same.

Fig. 3 is a side elevation showing the apparatus as it appears when a boat is being 90 lowered.

Fig. 4 is a side elevation of a modified form of the apparatus.

Fig. 5 is a plan view thereof.

Fig. 6 is a front view of a pulley block.

95 On the drawings the same reference letters and numerals wherever repeated indicate the same or similar parts.

a is the boat deck of the ship, *b* the boat, *c* the rope or other fall, *d* the winding winch 100 and *e* the pivoted davit.

In the arrangement, Figs. 1 to 3, the davit *e* is pivoted at *e*, at its lower end, in bearing brackets 1, 2, securely fastened to the deck and is capable of moving, in a vertical 105 plane, inboard and outboard, the inboard position being shown in full lines, at Fig. 1, and full outboard position in dotted lines. The partial outboard position is shown in full lines Fig. 3. Pivoted, at 3, to 110

the deck, by bracket 3^a, is a strut member 4 which, at its upper end, is secured by means of links 5 to the end of the davit. The strut member has a pulley 6 at its upper end and 5 the davit a pulley 7 at its end over both of which the rope or other fall *c* passes. Preferably, as shown, the davit would be made in two parts, and the strut member also in two parts and would work between the parts of 10 the davit. A stop 8 is provided on the strut member on which rests the davit when in its lowered or outboard position and stop pieces 9 are provided on the davit for the strut member when in its lowered position.

15 The davit is so pivoted that, when it is erect and the ship is on an even keel, a vertical line through its center of gravity will fall between the pivotal axis and the side of the ship with the result that the davit will 20 tend to fall outboard when the rope is paid out from the winch, and it is obvious (from Fig. 1) that, in falling from the vertical toward the horizontal position, it will move the boat outboard clear of the ship. As the 25 davit is allowed to move downward by the paying out of the rope, the strut member, owing to its link connection with the davit, moves along with it until it finally assumes the vertical position (see dotted lines Fig. 1) 30 the davit then resting upon the stops 8 and the boat hanging clear of the ship. In this position the boat may be lowered away clear of the ship by simply paying out the rope. When a boat is being raised the winding of 35 the rope raises the boat and eventually also moves the davit inboard the strut member being brought again to the position shown in full lines at Fig. 1 and resting on the stops 9. The boat is lowered into chocks 40 provided for its reception but not shown on the drawings.

It will be seen that, as the leverage of the davit member increases owing to its outboard movement, the support of the strut member correspondingly increases and it eases the load so that there is less liability of the davit breaking away at its pivots upon which there would, otherwise, be great stress.

50 In some cases, especially in large liners, it may be desirable to move the boat farther away from the ship's side when lowering it and, in order that this may be done, the pivots of the davit member are made so as 55 to move outward toward the ship's side thereby giving the maximum reach of the davit. This arrangement is shown at Figs. 4 and 5 the pivots 10 being shown in the inboard position in full lines and in the extreme outboard position in dotted lines. In 60 this case the davit *e* is provided with sliding blocks 10^a (or rollers, or equivalent) capable of traveling in guides 11 securely fastened to the deck, and the pivots 10 of the 65 davit (working freely in said sliding blocks)

are connected by means of a drag bar 12 to the strut member at a position some distance above the pivot 3 of the latter. As will be seen the strut member may, in this case, be pivoted at the side of the ship in a 70 strong bracket 13 and be capable of swinging through a vertical arc from the inboard position shown in full lines, Fig. 4, to the outboard position shown in dotted lines, same figure. With this arrangement the strut 75 member is not only linked, at its upper end to the upper end of the davit, by means of the links 5, but is also linked thereto by the drag bar 12. As a result a compound or dual motion takes place when the boat is 80 being lowered, the davit, as it moves downward, and the strut member, as it moves upward, causing a simultaneous movement of the pivots along the guides 11 with the result that the davit moves bodily and its pivots gradually travel toward the outside of the ship until, when fully lowered, they assume the position shown in dotted lines, 85 Fig. 4.

When the davit is at, say, the port side 90 and the ship has a list to starboard it is obvious the davit will not tend to fall outboard by gravity and to meet this requirement the guides and pivots may be carried on a hinged platform capable of being raised at the inboard end, by means of screw or other gear. 95

The winch employed may be of any suitable and well known type and be provided with a powerful self-sustaining brake so that a boat may be held in any position when 100 lowering. The winch may be operable by hand or by power.

If desired guys 21 may extend from the deck to the top of the strut member.

Fig. 6 shows a pulley block which I prefer to use with a single davit. This block 14 is made with arms 15 and stiffening webs 16 and a pin 17 is passed through the arm the spindle carrying a revoluble pulley 18 over which the fall *c* passes. The arms are 110 of such length that the slings 19, 20, from the fore and aft ends of the boat, do not converge closely together but are secured at some distance apart on the pin 17 thereby preventing tendency to strain the boat by 115 drawing its ends together. The webs 16 prevent the pin bending under the load.

Although I have shown methods of constructing the apparatus I do not confine myself thereto as the structural parts could be 120 altered as required to suit different types of ship.

What I claim as my invention and desire to secure by Letters Patent is:—

1. Apparatus for raising and lowering 125 ships' boats, comprising, in combination, a pivoted davit, a pivoted member, means connecting the davit to the member in such manner that as the davit moves downward the member moves upward, winding means 130

and a fall extending from said winding means over the upper ends of the member and the davit.

2. Apparatus for raising and lowering ships' boats, comprising, in combination, a pivoted davit, a pivoted member, means connecting the davit to the member in such manner that as the davit moves downward the member moves upward, winding means and a fall (from which the boat is suspended by a pulley block) extending from said winding means over the upper ends of the member and the davit.

3. Apparatus for raising and lowering ships' boats, comprising, in combination, a pivoted davit, a pivoted member, means connecting the davit to the member in such manner that as the davit moves downward the member moves upward, winding means and a fall from which the boat is suspended by a pulley block having laterally projecting arms and slings connecting the boat to said arms.

4. Apparatus for raising and lowering ships' boats, comprising, in combination, a pivoted davit, a pivoted member, means connecting the davit to the member in such manner that as the davit moves downward the member moves upward, winding means and a fall from which the boat is suspended by a pulley block having laterally projecting arms, a spindle in the arms and slings connecting the boat to said spindle.

5. Apparatus for raising and lowering ships' boats, comprising, in combination, a pivoted davit, a rigid strut member pivoted at its lower end and link means connecting the upper end of the davit to the upper end of the strut member in such manner that as the davit moves downward the strut member moves upward.

6. Apparatus for raising and lowering ships' boats, comprising, in combination, a pivoted davit, a double rigid strut member pivoted at its lower end and link means connecting the upper end of the davit to the upper end of the member in such manner that as the davit moves downward the member moves upward.

50 7. Apparatus for raising and lowering ships' boats, comprising, in combination, a

davit, guides, pivoted means connecting the bottom of the davit to the guides so as to be movable therealong, a pivotal strut member, and means connecting the strut member to the davit.

8. Apparatus for raising and lowering ships' boats, comprising, in combination, a davit, guides, pivotal means connecting the bottom of the davit to the guides so as to be movable therealong, a pivotal strut member, and means connecting the strut member to the upper end of the davit and means connecting it also to the lower end of the davit.

9. Apparatus for raising and lowering ships' boats, comprising, in combination, a davit capable of moving through a vertical arc, a strut member capable of moving through a vertical arc, means connecting the davit and the member so as to move in unison, winding means, pulleys on both the davit and the strut member and a boat fall extending from said winding means over said pulleys.

10. Apparatus for raising and lowering ships' boats, comprising, in combination, a davit capable of moving through a vertical arc and also of a lateral movement, a strut member capable of moving through a vertical arc, means connecting the davit and the member so as to move in unison, winding means, pulleys on both the davit and the strut member and a boat fall extending from said winding means over said pulleys.

11. Apparatus for raising and lowering ships' boats, comprising, in combination, a davit capable of moving through a vertical arc and also of a lateral movement, guides determining said lateral movement, a strut member capable of moving through a vertical arc, means connecting the davit and the member so as to move in unison, winding means, pulleys on both the davit and the strut member and a boat fall extending from said winding means over said pulleys.

In testimony whereof I affix my signature in presence of two witnesses.

CHARLES WILLIAM ALEXANDER TAYLOR.
